Specification of Letters Patent. Patented Jan. 20, 1920.

Application filed July 26, 1915. Serial No. 42,021.

To all whom it may concern:

Be it known that we, LIBANUS M. TODD and ARTHUR C. LA MAY, both of Rochester, in the county of Monroe and State of New York, have invented certain new and useful Improvements in Checkwriters; and we do hereby declare the following to be a full, clear, and exact description of the same, such as will enable any person skilled in the art 10 to which the invention appertains to make and use the same.

This invention relates to printing apparatus of the kind known as check protectors, or check writers, and more particularly, to 15 that kind of check protecting machines which is provided with printing characters adapted in coöperation with a platen to print the value upon the check and at the same time rupture the paper so that the latter may absorb the ink applied by the printing characters.

It is of prime importance in such machines that the type be plentifully supplied with ink so that the paper will be thoroughly 25 marked. It is also characteristic of these machines that they are frequently subjected to usage of an intermittent nature by inexperienced operators and without any regular attention, so that the supply of ink carried by the inking rolls is often allowed to become exhausted before it occurs to the operator to supply more ink, and checks printed by the machine in this condition are imperfectly protected.

It is therefore one object of this invention 30 to provide a machine of this type having a fountain inking mechanism of ink capable of keeping the printing characters abundantly supplied with ink sufficient for long 35 periods of use so that impressions taken from the machine will always be thoroughly inked and thus afford the best protection.

It is a further object of the invention to 40 provide a machine of this kind, of a more automatic and self-contained character having mechanism for automatically applying ink from the reservoir to the type characters in adjustable quantities and in proportion to the extent of use of the machine.

These and other objects will more fully 45 appear as the description proceeds, reference being had to the accompanying drawings forming a part of the specification, in which:—

Figure 1 is a top plan view of the machine, 55 partly broken away.

Fig. 2 is an elevation of the front side of the machine, partly broken away.

Fig. 3 is a plan view, partly broken away, showing the upper portion of the casing 60 swung back to expose the interior parts.

Fig. 4 is a central longitudinal section in elevation, partly broken away, showing one position of the inking rolls.

Fig. 5 is a similar view showing the ink- 65 ing rolls in another position.

Fig. 6 is a sectional elevation showing the means for actuating the platen.

Fig. 7 is a sectional elevation on the line 7—7 of Fig. 5. 70

Fig. 8 is a sectional elevation taken on line 8—8 of Fig. 5.

Fig. 9 is a sectional elevation of a portion of the machine on the line 9—9 of Fig. 4.

Fig. 10 is a perspective view of the ink- 75 ing rolls.

Fig. 11 is a perspective view of a retaining member for the ink rolls.

Fig. 12 is a sectional view of a modified form of ink reservoir. 80

In the present embodiment of the invention the numeral 20 is used to designate, generally, the lower or base portion of the casing, and 21 denotes an upper casing portion having a hinged connection 22 (Fig. 6) 85 with the base portion 20, so that the upper portion of the casing may be swung back to afford access to the interior parts. In operation these portions of the casing are firmly secured together by any suitable device, and, in the present instance, a screw 23 (Figs. 4 and 5) is shown for that purpose.

The upper and lower portions of the casing are separated by a work receiving slot 24 below which, on the base portion 20, is a 95 printing bed 25 over which the work moves in its passage through the machine. The bed 25 has an opening 26 through which is adapted to be projected a platen wheel 27 (Figs. 3 and 8) rotatably carried by a yoke 100 member 28 which is adjustably secured near one end of a shaft 29. This shaft is journaled in lugs 30 depending from the printing bed (Fig. 3) and near its outer end the shaft has fixed thereto a hub 31 from which extends horizontally an arm 32 adapted to contact with the printing bed to arrest the downward movement of the platen so that

it lies normally with its top even with or just below the upper surface of the printing bed. The platen is urged into lowered or inactive position by a spring 33 (Figs. 3 and 5 6) attached at one end to the casing and at its other end to an arm 34 extending upwardly from the hub 31 and adapted at its upper end to contact with the outline of an actuating cam 35 adjustably secured on a 10 shaft 36 extending longitudinally of the upper portion of the casing and journaled at its ends therein. As the shaft 36 is revolved the cam 35, once in each revolution of the shaft, actuates the arm 34 and so raises the platen 27 into contact with type forms supported in the casing above, which will now be described.

Slidably mounted on the shaft 36 is a type carrier having a cylindrical surface 37 (Figs. 20 3, 4 and 8), and ends 38 having a sliding bearing on the shaft. Secured to the surface 37 is a type plate 39 provided with a plurality of parallel type forms, indicated generally at 40, extending circumferentially 25 of the carrier in parallel spaced relation so that they may be brought individually and selectively, by the shifting of the carrier along shaft 36, into position to coöperate with the platen upon rotation of the carrier. 30 The latter is provided with a key 41 sliding in a keyway in the shaft 36 and serving as a driving connection between the carrier and shaft when the latter is rotated.

The means for rotating shaft 36 comprise 35 a gear 42 at the forward end of the shaft (Fig. 3) meshing with a gear 43 fixed to the inner end of a stub shaft 44 which is journaled in the upper portion of the casing and carries exteriorly thereof an actuating 40 crank having a handle 45.

The type carrier is shifted longitudinally to select the type forms by means of an elongated yoke 46 provided with depending ends 47 rotatably and slidably journaled on the shaft 36 and closely engaging the ends 45 of the carrier.

The means for shifting the yoke 46 comprises a plate 48 attached to a lug 49 on the yoke (Figs. 4 and 7) and extending through 50 an opening 50 in the casing and carrying a handle 51. The plate 48 is extended horizontally to form a pointer 52 above a dial 53 on top of the casing which has markings thereon corresponding to the various 55 type forms on the carrier. By means of the handle 51 the pointer 52 may be moved into alignment with any one of the markings on the dial, thereby shifting the carrier to bring the corresponding type form into position to 60 coöperate with the platen.

The dial 53 is supported on a plate 54 carried on a flange 55 extending upwardly from the top of the casing, and the plate 54 is provided with an elongated slot at the 65 edges of which the plate is turned down-

wardly to form flanges 56 serving as guides for a roller 57 secured upon the yoke 46 and serving to prevent rotation of the latter with the shaft 36.

The printing surfaces of the type forms 70 and the platen are provided with coöperating serrations which, as indicated on the platen in Fig. 3, preferably extend circumferentially of both members, and these serrations are adapted to mesh with each other, 75 or register, during the printing contact to disrupt the fibers of the paper and simultaneously print and feed it. As these serrations are comparatively small there is provided a means for bringing the selected type 80 form precisely into registering position with the platen, and for locking it in this position during the printing operation. Depending from the flange 55 of the casing is a comb or rack 58 having recesses spaced to 85 correspond with the spacing of the type forms on the carrier, and pivoted at 59 on a lug 60 of the carrier yoke 46 is a coöperating dog 61 having a beveled end 62 adapted to be moved into locking engagement with the recesses of the rack 58. Dog 61 is normally held in lower or inactive position by a spring 63, in which position the bottom of the dog contacts with the outline of a cam 64 on the end of the type carrier. This cam 95 is so designed that as the type carrier is rotated the dog is moved into engagement with the rack 58 just previous to contact between the type form and platen, and by means of the beveled surfaces of the dog and rack 100 the type form is drawn accurately into position and locked until it passes out of contact with the platen when the cam allows the dog to be retracted, after which the carrier may be shifted longitudinally to select 105 another form.

At the commencement of the printing operation the work is located on a table 65 (Fig. 3) sliding longitudinally upon guide rods 66 at the front of the casing. As this 110 table forms no part of the present invention a detailed description thereof is unnecessary. Attached to the upper portion of the casing and extending horizontally above the table is a plate 67 (Figs. 1 and 8) to which is pivoted at 68 a plate 69 provided with a gage opening 70 through which the line to be printed is sighted in adjusting the position of the work upon the table 65. The plate 69 is extended within the casing to 115 form two spaced resilient fingers 71 bearing at each side of the printing line upon a small roller 72 rotatably journaled on a plate 73 secured on the printing bed. The fingers 71 bear resiliently upon the work and serve to 120 guide and hold it against inadvertent movement on the printing bed as it is fed forward by the printing couple, but as these fingers must be raised to allow the insertion or removal of the work the plate 69 is pro- 125 130

vided with an upwardly extending leaf 74 with which engages a hook 75 on a spindle 76 journaled in brackets 77 (Fig. 3) in the upper portion of the casing. The spindle 76 5 carries a fixed arm 78 (Fig. 3) which is pivoted at 79 to a plate 80 which extends upwardly and is provided with a plunger 81 projecting above the casing. By depressing the plunger 81 the pressure fingers 71 10 are raised away from the roll 72 so that the work may be freely inserted or withdrawn from the machine.

For applying the ink to the type forms there is provided a pair of short inking rolls 15 82 and 83. The type forms are adapted to print, some in one color of ink and some in another, and to this end are grouped according to color, as indicated in Fig. 3, where the reference character 40^r designates type forms printing, say, in red ink, and the character 40^b type forms printing in black ink. The ink roll 82 is provided for inking the forms 40^b, and the roll 83 for inking the forms 40^r.

25 The roll 82, preferably, is rotatably mounted on a spindle 84 (Fig. 10) carried in a bracket 85 projecting from a sleeve 86 which is rotatably supported upon a round bearing portion on the angular rod 87. This 30 rod extends longitudinally of the carrier yoke 46 and is rotatably journaled at its ends in arms 88 and 89 extending from the yoke. Roll 82 is normally urged downwardly toward the type forms by spring 90, but its 35 movement in this direction is limited by the contact of a lug 91 on the arm 88 with the end of a slot in the sleeve 86, see Fig. 10.

The roll 83, preferably, is rotatably carried on a spindle 92 fixed in a bracket 93 40 which extends from a sleeve 94 slidably, but non-rotatably carried by the angular section of the rod 87. The rod 87 projects beyond the supporting arm 89 and has fixed at its end an arm 95 (Fig. 7) which is drawn upwardly against a stop pin 96 by means of a spring 97 attached to the arm and to the yoke 46. By this means the roll 83 also is 45 normally urged downwardly in position to contact with the type forms as the latter are 50 rotated for printing.

Each of the inking rolls is detachably mounted so that it may be conveniently withdrawn for cleaning. To this end each of the brackets 85 and 93 is provided with 55 a bore, as indicated at 98, Fig. 10, in which the spindle of the roll is inserted, and the spindle is provided with a circumferential recess 99 with which is adapted to engage a spring actuated plunger 100 having a pin 60 101 projecting through a slot 102 in the bracket so that the plunger may be retracted and the roll with its spindle readily removed from the bracket.

It is very advantageous in operation to 65 maintain an inking roll of the proper color

opposite the printing point so that the type form selected for impression upon the paper will inevitably receive a supply of ink during its rotation toward the platen just previous to the impression. With this object in view a construction has been provided for moving the rolls automatically in co-operation with the selective movement of the carrier. Pivoted to the top of the casing is a plate 103 pressed downwardly by a 75 spring 104 carrying at its lower edge a cam surface 105 having a high portion 106, and also a cam surface 107 discontinued to form a recess at 108. The opposite end of the plate 103 is curved at 109 to insure proper 80 engagement with a pin 110 fixed to the sleeve 86 and adapted to engage the plate as the carrier is moved toward the left in Fig. 5. The sleeve 94 also is provided with a projecting member 111 adapted to engage with 85 the cam surface 107 as the carrier is moved toward the right, as seen in Fig. 4. There is also provided a stop member 112 (Fig. 4) fixed to the casing in position to engage 90 the member 111 to limit the movement of the roll 83 toward the left, as shown in Fig. 4.

The roll 82 is long enough to span the small group of forms 40^b so that this roll does not move longitudinally relatively to 95 the type carrier, and as the carrier is moved to place one of the latter forms in printing position the roll 82 is moved with it and the pin 110 engaging the surfaces 109 and 105 slides freely over these surfaces, merely 100 raising the plate 103. As the carrier is moved toward the right, as seen in Fig. 4, to place one of the forms 40^r in printing position, the roll 83 moves with the carrier, due to its frictional engagement with the 105 rod 87, and the member 111 riding over the cam surface 107 engages the high portion 106 and comes to rest in the recess 108 which serves to retain this roll opposite the platen in position to ink any one of the forms 40^r 110 which is brought into printing position by the shifting of the carrier, and it will be understood that during this shifting movement the rod 87 slides freely through the sleeve 94. When, however, the carrier is 115 shifted to again bring the ink roll 82 opposite printing position the pin 110 raising the plate 103 releases the member 111 and the roll 83 which is moved toward the left (Fig. 4) to allow the roll 82 to take its place. 120 Thus the roll 83 is automatically picked up, carried to printing position and retained there when printing with one of the type forms 40^r, but is released and moved out of the way whenever the carrier is shifted to 125 bring one of the forms 40^b and roll 82 to printing position.

The casing is provided opposite the path of movement on the printing rolls with an opening 113 having a closure 114 pivoted at 130

1 its bottom to the casing and carrying a small latching member 115, Fig. 3. This closure 114 carries a fountain inking device for each of the rolls comprising sockets 116 and 117 5 in which the inking devices are supported, and as these devices are the same in construction a description of one will be sufficient.

2 The ink reservoir or container is, preferably, a cylinder 118 adapted to slide vertically in the socket 117, and the reservoir has a circular opening or valve seat 119 in its bottom in which is adapted to rest a ball 120 serving to close the opening but projecting below the bottom of the reservoir so 10 that it may be rotated by contact with the ink roll, or even raised from its seat thereby to permit the escape of ink through the opening 119. The reservoir 118 is provided 15 with a screw cap 121, and a rod 122 having a threaded engagement with this cap extends through the reservoir into proximity to the ball 120. By turning the rod 122 and so adjusting its vertical position, the distance 20 of movement of the ball 120 from its seat is controlled to regulate the flow of ink. The upper end of rod 122 carries a finger 123 adapted to move between stop pins 124 over 25 a scale marked on the cap as a convenient 30 means for marking the position of adjustment of the controlling rod.

3 For filling the reservoir with ink the cap 121 is provided with an opening in which is threaded the closure 125. The member 35 125 has a central recess 126 extending upwardly from its bottom and communicating with a small aperture 127 opening through the side of the member 125, just below its head. By slightly unscrewing the closure 40 member 125 until the aperture 127 comes above the top of the cap 121 the air may be allowed to enter the reservoir 118 through the aperture 127, thus forming an air vent 45 for the ink reservoir, which may be opened or closed as found desirable in the operation of the machine.

5 In order to adjust the lowermost position in the socket 117 of the sliding reservoir 118 so that the ball 120 will be in position to contact properly with the inking roll regardless of the amount of wear to which the latter has been subjected, the socket 117 is provided with a lug 128 in which is adjustably threaded a screw 129 having a flange 55 130 adapted to engage beneath the flange 131 on the reservoir 118. The screw thus forms a stop of adjustable height for limiting the downward movement of the reservoir 118, but the latter is free to be moved upwardly 60 in its socket whenever the ball 120 is raised by the inking roll into contact with the controlling rod 122.

65 Referring to the modified form of ink reservoir shown in Fig. 12, there is provided, as before, a reservoir 118 having a

7 valve seat 119 adapted to be closed by ball 120. Into the upper end of this reservoir is threaded a cap 132 serving as a supporting socket for a glass container 133 which is closed at its upper end by a cap 134. 70 Threaded into the cap 134, and also into the lower cap 132, is a tube 135 which serves to draw these two caps tightly into contact with the ends of the container 133, gaskets being provided to make the joints fluid 75 tight. Openings 136 are provided in the lower portion of the tube 135 to allow the ink to flow from the upper to the lower container. Supported in the tube 135 by an adjusting thread is a controlling rod 137 extending into proximity to the ball 120 for controlling the amount of opening of the valve, and the rod 137 has screwed upon its upper end a finger 138 secured in adjusted 80 position on the rod by means of a lock nut 139 and adapted to move over an indicating scale upon the top of cap 134 between stop pins 140 for convenience in adjusting the position of the controlling rod 137.

85 The cap 134 is provided with a filling 90 opening closed by member 142 provided with an air vent 141 similar in construction and purpose to that described above in connection with the preferred form of the invention. This modified form of construction 95 is designed to be used for the purpose of increasing the fluid holding capacity of the fountain inking device, for use in machines where the output of work is quite 100 large.

105 The operation of the machine will be readily understood from a brief explanation in connection with the above description of the construction. A check having been placed in proper position upon the supporting table 65, the handle 51 is moved to position the pointer 52 successively over the various type forms desired to be impressed upon the paper, and after each such adjustment the crank 45 is rotated to rotate the type cylinder and raise the platen into rolling contact with the particular type form selected for printing. The check is thus simultaneously printed and fed through the machine. 110

115 During the shifting of the type carrier to bring the various type forms selectively into printing position, the inking roll of the color corresponding to the selected type form is automatically brought opposite the printing point, in position to roll against and ink the selected type form as it moves into contact with the paper, the other roll being moved aside. The ink reservoirs, in the present embodiment of the invention, 120 are so located that whenever the roll 83 is moved from opposite the printing position it is carried opposite its ink reservoir. When the roll 82 is moved from opposite the printing position it is, for certain posi- 125 130

- tions only of the type carrier, brought opposite its reservoir, this roll having fewer forms to ink and so not requiring to be supplied so often. When each roll is opposite its reservoir, the contact of the type forms with the roll at each rotation of the carrier raises the roll slightly, as shown in Fig. 9, bringing it into contact with the ball 120 so that the latter is rotated, and
- 10 carries a film of ink from the reservoir to the roll, or else the ball 120 is raised slightly from its seat permitting a somewhat larger quantity of ink to be carried by it to the inking roll, depending upon the position of
- 15 vertical adjustment of the rod 122. When the ball 120 is raised by the inking roll into contact with the rod 122, the reservoir 118 is adapted to rise in the socket 117 to prevent excessive pressure between the inking
- 20 roll and the ball 120. By means of the adjusting screw 129 the reservoir 118 may always be supported in such a position that the inking rolls will contact with the ball when they are raised by engagement with
- 25 the type, regardless of any variation in size of the rolls due to wear.

The supplying of ink to the rolls of a check writing machine whenever they become too dry to afford a protective impression of the paper, and with just the right quantity of ink, is the most important and the most troublesome feature of the operation of a machine of this kind. This invention combines with a check writing machine a mechanism which attends to this requirement automatically by keeping the rolls uniformly and constantly supplied with the proper quantity of ink in proportion to the amount of printing done by the machine, and without attention from the operator over long periods of use, thus adding very greatly to the utility and efficiency of the machine.

Having thus described our invention, what we claim as new and desire to secure by Letters Patent is:—

1. The combination of a printing couple comprising a rotatable type carrier and a platen, the members of said printing couple having a relative movement to bring various type forms on the carrier, selectively, to a common position for co-operation with the platen, and having also a relative printing movement to impress the selected type forms upon the work; a fountain ink container; an inking device for applying ink to the type forms; and means for supplying ink from said fountain container to said inking device actuated automatically by the rotary movement of said type carrier.

2. The combination of a printing couple comprising a type carrier and a platen, said carrier and platen having a relative shifting movement to bring various type forms, selectively, to printing position, and having

also a rotary movement to impress the work; a fountain ink container; means connected with said container for supplying ink therefrom; and a device for applying ink to said type forms adapted to be moved automatically into actuating engagement with said ink supplying means by contact with the type forms during said rotary movement of the printing members.

3. In a printing apparatus, the combination of a casing, a rotatable type carrier therein, a fountain ink container supported by said casing, means connected with said container for supplying ink therefrom, and an inking device arranged for contact with the type forms on said carrier during the rotation of the latter to apply ink to said type forms and to be moved by the rotary movement of the type forms into engagement with said ink supplying means for actuating the latter and automatically supplying ink from said container to said inking device.

4. In a printing apparatus, the combination of a type carrier having its type forms arranged in a plurality of groups, and having a shifting movement to bring the forms of either group, selectively, to a common printing position, a plurality of shiftable inking devices, each coacting exclusively with a corresponding one of said groups of forms on the carrier, means for automatically maintaining the corresponding one of said devices in position to ink the selected type form, a plurality of fountain ink containers one for each of said inking devices, and means for supplying ink from each container to its corresponding inking device automatically during the operation of the machine.

5. In a check writing machine, a type carrier shiftable to bring various type forms selectively to a common printing position, a roll for inking said type forms adapted to be moved when said carrier is shifted, means for retaining said roll against movement with said carrier, and means for rendering said retaining means inoperative to permit movement of said inking roll upon movement of said carrier.

6. In a printing apparatus, a type carrier shiftable to bring various type forms, selectively, to a common printing position, a device for inking said type forms adapted to be moved when said carrier is shifted in either direction, means for holding said inking device against movement during movement of the carrier in one direction, and means for rendering said holding means inoperative to permit movement of said inking device when the carrier is moved a predetermined distance in said direction.

7. In a check writing machine, a type carrier shiftable to bring various type forms, selectively, to a common printing position, a

6
roll for inking a portion of said type forms adapted to be moved when said carrier is shifted, means for retaining said roll against movement with said carrier in position to 5 ink a selected type form, a roll for inking another portion of said type forms movable with said carrier, and devices for releasing said retaining means to permit said second roll to replace said first roll when any of 10 10 said other portion of the type forms is brought to printing position.

8. In a printing apparatus, a type carrier shiftable to bring a plurality of type forms, selectively, to a common printing position, a 15 plurality of inking devices, one for each of a corresponding portion of said type forms, and adapted to be moved individually to inking position when one of the corresponding portion of type forms is selected for 20 printing, and means for automatically displacing an inking device from said inking position and substituting another therefor when the carrier is shifted to select one of a different portion of said type forms.

25 9. In a printing apparatus, a type carrier shiftable to bring various type forms, selectively, to a common printing position; a plurality of inking devices each movable individually to a common operative position 30 for applying ink to a corresponding portion of said type forms; means for retaining an inking device in said operative position when printing with one of the corresponding portion of the type forms; and means 35 for automatically substituting therefor a different inking device when printing with one of a different portion of the type forms.

10. In a printing apparatus, a type carrier shiftable to bring various type forms, 40 selectively, to a common printing position; a plurality of inking devices, each for a portion of said type forms and carrying ink of a different color; means for moving said devices individually to a common inking position when one of the corresponding portion of type forms is selected for printing; and means for retaining an inking device in said inking position and for automatically displacing it and substituting another therefor 45 when printing with one of a different portion of said type forms requiring ink of a different color.

11. In a check writing machine, a type carrier provided with a plurality of type 55 forms, some for printing in ink of one color, some in ink of a different color, the forms being arranged in groups according to the different colors, a platen, said carrier being movable to bring the type forms individually and selectively to a common position for coöperation with the platen, a plurality of inking rolls for applying ink of the proper color to each group of said type forms, and devices for positioning one roll 60 65 in inking position when printing with the

type forms of the corresponding group to ink the latter in succession, and for automatically substituting another roll of the proper color when printing with the type forms of a different group. 70

12. The combination of a platen; a type carrier having a shifting movement to position various type forms, selectively, for coaction with the platen, and having also a printing movement; an inking device for 75 applying ink to the type forms, said device being shiftable with said carrier to preserve its position with relation to the type forms; a fountain ink container; and ink supplying means actuated automatically by said printing movement of the carrier for supplying ink from said container to said inking device.

13. The combination of a type carrier having a rotary movement and also a movement 85 parallel with its axis; a plurality of type forms on the carrier; a platen coacting with the type forms; an inking device for applying ink to said forms, said device being movable with said carrier in the axial movement 90 of the latter to preserve its position with relation to said forms; a fountain ink container; and ink supplying means actuated automatically by said rotary movement of the carrier for supplying ink from said container to said inking element. 95

14. The combination of a platen; a carrier provided with two groups of type forms, said carrier having a shifting movement to position the forms of either group 100 selectively for coaction with the platen, and having also a printing movement; a fountain ink container for each group of type forms; inking devices, one for each group of forms, for applying ink to the 105 forms thereof, said devices being movable alternately to position to ink the type form selected for printing by said shifting movement of the carrier; and ink supplying means actuated automatically by said printing movement of the carrier for supplying ink from said container to said inking device. 110

15. In a printing apparatus, a type carrier shiftable to bring various type forms, 115 selectively, to a common printing position, a device for inking said type forms adapted to be moved when said carrier is shifted in either direction, means for holding said inking device against movement during movement of the carrier in one direction, and means for rendering said holding means inoperative during movement of the carrier in the opposite direction.

16. In a printing apparatus, a type carrier shiftable to bring various type forms, selectively to a common printing position; an inking roll for inking a portion of the type forms and movable with relation to its corresponding forms; a second inking roll. 120 125 130

for inking another portion of the type forms, and immovable with relation to its corresponding forms; and means for disposing either of said inking rolls in position 5 to ink any one of its corresponding portion of type forms brought to printing position.

17. In a printing apparatus, a type carrier having an inoperative position and movable from said position to bring various type 10 forms, selectively, to printing position; an inking roll for said forms movable to inking position by said movement of the carrier when the latter is moved from inoperative position to bring one of its forms to 15 printing position; retaining means for retaining said roll in inking position during subsequent selective movement of the carrier; and releasing means for said roll by means of which it may be moved from inking 20 position when said carrier is moved to inoperative position.

18. In a machine of the class described, the combination with a rotatable type carrier provided with a plurality of circumferentially extending word type forms, of a platen constructed to print from a single word type form during rotation of the type carrier, means for moving the type carrier to

position any line of type opposite the platen and for then rotating the carrier to carry 30 the type against the platen, a fountain ink container having a ball and socket device operable by rotating the ball to draw ink from the container, and an inking roller first moved into contact with the ball and then 35 rotated by printing movement of the type carrier whereby to rotate the ball and draw ink from the container.

19. In a machine of the class described, the combination with a cylindrical type carrier having a plurality of circumferentially extending word type forms, a platen, means for moving the type carrier in an axial direction to position any desired type form opposite the platen and then rotating the carrier to print, a manipulative device for imparting the axial selecting movement to the type carrier, a plurality of ink applying devices for applying inks of different colors, and means controlled by the manipulative 40 device for positioning the desired ink applying device to coöperate with the type form set in position to coöperate with the platen. 45
